UNITED STATES PATENT OFFICE.

ELOF JOHNSON, OF BROOKLYN, NEW YORK.

DEVICE FOR INCREASING THE EFFICIENCY OF INTERNAL-COMBUSTION ENGINES.

Application filed October 7, 1922. Serial No. 593,038.

This invention relates to improvements in devices for selectively introducing different fluids, either liquid or aeriform, into the intake pipe of an internal combustion engine, and the object thereof is to provide a convenient device by means of which a suitable selected fluid may be thus introduced into the intake of the engine for the purpose of increasing the efficiency of the engine.

More specifically one of the objects of the invention is to produce a device which may be utilized selectively to aid in obtaining perfect combustion of the fuel by the admission of humidified air into the cylinder of the engine and which also may be employed to keep the engine free of carbon deposits and to aid in removing the carbon deposits from the walls of the cylinder.

A further object of the invention is to provide a device of the character described which can be selectively arranged to provide means for priming the engine for starting purposes, or for accelerating the speed, or controlling the character of the explosive mixture admitted to the engine.

A further object of the invention is to provide a convenient and inexpensive device of the character above described which may be readily applied to any of the usual types of internal combustion engines such, for example, as the engine of an automobile.

A further object of the invention is to provide a novel means for controlling the adjustment of the valves which regulate the delivery of the selected fluid or fluids to the intake of the engine.

Other objects and features of the invention will more fully appear from the following description and the accompanying drawing and will be particularly pointed out in the claims.

A preferred embodiment of the invention is conventionally illustrated herein as applied to an automobile engine.

In the drawings:

Fig. 1 is a conventional illustration of the invention applied to an automobile;

Fig. 2 is a vertical sectional view of the fluid-containing reservoir, the inlet pipe for the air and outlet conduits for the fluid being shown in elevation;

Fig. 3 is a similar view of the fluid-containing reservoir comprising also a receptacle to contain a liquid differing from the

liquid contained in the main body of the reservoir;

Fig. 4 is a horizontal sectional view on line 4—4 Fig. 2 of the portion of the conduits through which the fluid from the reservoir is conducted from the reservoir and also showing in elevation a broken away section of the conduit or tube leading therefrom to the intake of the engine; and,

Fig. 5 is an underneath plan view of a plate adapted to be mounted upon the instrument board of the automobile, showing means for controlling the adjustment of the valves which regulate the supply of fluid to the engine intake;

Fig. 6 is a detail of the connection to the manifold.

It is well known that internal combustion engines may be operated more efficiently especially in dry weather by supplying humidified or moisture-laden atmosphere to the intake of the engine. It is also well known that by introducing certain liquids, such as, water or kerosene in greater or less volume, into the intake of the engine the carbon formed in the combustion chamber will be reduced, or where deposited upon the walls of the cylinder will be softened and conveniently removed therefrom.

The principal object of the invention is to provide means adapted to be controlled by the operator of the engine which may be employed selectively to introduce either humidified air or water, or both, into the manifold of the engine in proper proportion to maintain the highest efficiency and prevent carbon deposits or to remove carbon deposits previously made. This is accomplished in the preferred embodiment of the invention illustrated in Figs. 1 and 2 by providing a reservoir 1, preferably in the form of a cylindrical container, which is supported upon suitable brackets 2 and 3 upon the dash of the engine, or in any other suitable manner, at a convenient distance from the intake of the engine, and providing a conduit or conduits leading from said reservoir to the intake or manifold of the engine adapted to deliver the selected fluid to said intake.

The reservoir 1 desirably is partially filled with a suitable liquid 4, such as, water, and is provided with an air inlet 5 leading through the wall of the reservoir above the level of the liquid downwardly into the

liquid and terminating in a substantially horizontal portion 6 located well beneath the level of the liquid and preferably approximately at the bottom of the reservoir, and 5 provided with a series of apertures 7 through which the air may be drawn upwardly through the liquid into the upper portion of the reservoir by the suction of the engine. 10 The reservoir 1 preferably is provided 10 with a removable cover 8 which may be screwed or otherwise fastened upon the upper end of the wall of the reservoir. The cover 8 is provided with one or preferably two upwardly extending hollow bosses 9 and 15 10 which are provided respectively with screw threaded caps 11 and 12 which hermetically close the apertures in said bosses. The reservoir and its cover may be made of sheet metal construction in the usual manner. 20

The reservoir is provided with a plurality of upwardly extending conduits 13 and 14 which desirably are cast integral with a head 15 having ducts 16 and 17 which lead to a 25 common delivery outlet 18 which is connected by a nipple 19 with a pipe 20 which leads to the intake or manifold 21 of the engine. The ducts 16 and 17 are counterbored to provide 30 valve seats 22 and 23 for valves 24 and 25 which are located when seated between the upwardly extending portions 13 and 14 of the conduits and the ducts 16 and 17 respectively. 35

The valves 24 and 25 are provided with 35 suitable valve stems 26 and 27 to which are connected suitable rods 28 and 29 extending through the dash board and instrument board of the automobile and are provided with suitable knobs 30 and 30* by which they 40 may be manipulated. The valves 24 and 25 are normally held in their seats by helical springs 31 and 32 which are interposed between the respective valves and screw threaded plugs 33 and 34 seated in the ends of the 45 counterbored portions of the head 15.

As illustrated in Fig. 2 the sections 13 and 50 14 of the conduits are secured to and extend a short distance through the cover 8 of the receptacle. The lower ends of the walls of the conduits 13 and 14 desirably are internally threaded and a pipe 35, which is detachably screwed into the conduit section 13, extends below the surface of the liquid 4 55 preferably to a point adjacent the bottom of the reservoir.

In the operation of the device illustrated 60 in Figs. 1 and 2 the valve 24, which controls the duct leading from the conduit 14, may be opened by pulling upon the knob 30 so that the suction of the engine will draw the air from the upper portion of the reservoir. The exhaustion of air from the upper portion of the reservoir creates a partial vacuum which causes air to be drawn through the 65 inlet pipe 5 and delivered into the tank

through the apertures 7 from which it rises through the liquid in the reservoir and becomes more or less charged with the vapor of the liquid. When the reservoir contains water this humidified air is progressively drawn through the conduit 14, duct 17 and conduit 20 into the intake of the engine, thereby increasing the moisture content of the charge and providing a more efficient explosive mixture. 70 75

If it is desired to introduce water directly into the engine intake the valve 25 may be withdrawn so that the suction of the engine will draw water from the reservoir through the conduit 13, the duct 16 into the 80 pipe or conduit 20 which will deliver it directly into the engine intake. Thus a sufficient amount of water may be introduced into the engine to reduce or remove the carbon deposit. 85

The valves 24 and 25 may thus be manipulated either to supply only humidified air or only water to the engine intake, or to supply a limited amount of air and a limited amount of water to the engine intake as may 90 be desired.

Another feature of the invention consists in providing a novel frictional device for controlling the adjustment of the valves 24 and 25. As illustrated herein a plate 36 is 95 provided which has a narrow marginal flange 37 extending downwardly from its under face. The rods 28 and 29, which are connected respectively to the valve stems 26 and 27, extend through this plate and are engaged by hooked end portions 38 and 39 of a spring 40 which is coiled around a suitable stud or screw 41 by means of which the plate is secured to the instrument board. The hooked end portions of these springs serve 100 to retain the rods at any desired adjustment so that the valves 24 and 25 may be properly positioned to regulate the desired amount of vapor-laden air or liquid supplied to the engine. 105 110

While the apparatus has been described as adapted to supply humidified air and water to the engine intake it may, of course, be utilized to supply other liquids and vapors; for example, a high grade fuel such as pure gasoline may be placed in a tank and either the vapor thereof or the liquid itself supplied to the intake of the engine either as a primer for starting the engine or to increase the efficiency of the engine while 115 running. 120

In Fig. 3 a modified construction is illustrated in which a separate receptacle is provided for a priming fluid, such as, high grade gasoline. In this construction a receptacle 42, preferably of sheet metal, is provided having a flange 43 which is detachably secured by screws 44 to the under face of the cover 8. The upper end of the receptacle encloses the end of the portion 14 125 130

of the conduit and a pipe 45, which is screwed into the conduit 14, extends beneath the level of the liquid 46 in said receptacle preferably to a point adjacent the bottom thereof.

In the use of the device illustrated in Fig. 3 the conduit 13 desirably communicates with the upper portion of the reservoir so that by manipulating the valves 24 and 25 as above described either the priming liquid or the humidified air may be introduced into the engine. By removing the cover and substituting the pipe 47, illustrated in dotted lines in Fig. 3, water or other suitable liquid may be directly introduced into the manifold for the purpose of removing carbon in the manner above described.

It will, therefore, be observed that the invention may be adapted selectively to deliver various fluids to the intake of the engine and that such fluids may be either a priming fluid, an aeriform fluid comprising the vapor of a selected liquid, or the liquid itself. Thus the invention may be employed to increase the efficiency of the engine by adding moisture to the charge, or may be employed to reduce and remove the carbon from the combustion chamber of the engine, or may be used to prime the engine for starting, or to supply a high grade fuel to increase the efficiency of the engine while running.

In order to assist in breaking up or atomizing the liquid drawn into the manifold it is desirable that the pipe connection protruding into the manifold shall be provided with a spray nozzle such as shown for example in Figure 6. This figure shows in an enlarged detail a nozzle 48 to which the pipe 20 is connected and which is screwed into the wall of the manifold 21 and carries at its inner end the spray head 49.

The tank 1 may be provided if desired at the bottom with a suitable means for draining or cleaning out the reservoir. For that purpose there is illustrated an outlet pipe 50 in the bottom wall of the tank. A valve member 51 is threaded into the pipe 50 and is movable to open and close the passageway from the tank into the pipe 50 and out through a drainage opening 52 in the side of the pipe.

It will be understood that the embodiment of the invention disclosed herein is of an illustrative character and is not restrictive and that various changes in form, construction and arrangement of parts may be made within the spirit and scope of the following claims.

Having thus described my invention what I claim as new, and desire to secure by Letters Patent, is:

1. A device operable selectively to supply different fluids to the intake of an internal combustion engine by inspiration, comprising

ing a closed reservoir partially filled with water, an air inlet leading into said reservoir in proximity to the bottom thereof and below the level of said water, conduits leading respectively from below and above the level of said liquid and communicating with a single pipe leading to said engine intake and valves in said conduits operable respectively to permit the delivery of water or humidified air to said engine intake. 70 75

2. A device operable selectively to supply different fluids to the intake of an internal combustion engine by inspiration, comprising a reservoir partially filled with a liquid, means for introducing air into said reservoir below the level of the liquid, a cover detachably secured to the top of said reservoir having a plurality of conduits, one of said conduits including a pipe section extending below the level of the liquid in said reservoir and removably mounted in said cover and valves in said conduits operable respectively to permit the delivery of liquid or air containing the vapor of said liquid to said intake. 80 85

3. A device operable selectively to supply different fluids to the intake of an internal combustion engine by inspiration, comprising a reservoir partially filled with water and a receptacle within said reservoir containing a combustible liquid, means for introducing air into said reservoir below the level of said water, a cover removably secured to the top of said reservoir, a plurality of conduits mounted on said cover communicating with said reservoir and leading to the intake of the engine, said conduits comprising respectively detachable sections or pipes located within said reservoir adapted to be selectively arranged to extend beneath the level of the water or beneath the level of the combustible liquid in said receptacle or when removed to communicate with the reservoir above the level of the water. 90 95 100

4. A device operable selectively to supply different fluids to the intake of an internal combustion engine by inspiration, comprising a reservoir partially filled with water and a receptacle removably mounted in said reservoir containing a combustible liquid, means for introducing air into said reservoir below the level of said water, a cover removably secured to the top of said reservoir, a plurality of conduits mounted on said cover communicating with said reservoir and leading to the intake of the engine, said conduits comprising respectively detachable sections or pipes located within said reservoir adapted to be selectively arranged to extend beneath the level of the water or beneath the level of the combustible liquid in said receptacle or when removed to communicate with the reservoir above the level of the water. 110 115 120

5. A device operable selectively to supply 130

different fluids to the intake of an internal combustion engine by inspiration, comprising a closed reservoir having portions containing the respective fluids, conduits leading respectively from the portions of said reservoir containing said different fluids and communicating with the intake of the engine, valves in said conduits, rods connected to said valves extending through a fixed support, manually operable means for reciprocating said rods and a spring having portions frictionally engaging said rods acting to retain the same in adjusted position.

6. A device operable selectively to supply different fluids to the intake of an internal combustion engine by inspiration, compris-

ing a reservoir to receive a liquid, means for introducing air into said reservoir below the level of the liquid therein, a cover removably secured to the top of the reservoir, a plurality of conduits mounted on said cover communicating with said reservoir and leading to the intake of the engine, said conduits comprising a detachable pipe section located within the reservoir to extend beneath the level of the water therein and valves in said conduits operable respectively to control the fluid delivered therethrough to the intake of the engine.

In testimony whereof, I have signed my name to this specification.

ELOF JOHNSON.
